UNITED STATES PATENT OFFICE

WILLIAM RUSSELL DEGENHARDT, OF LONDON, ALLAN FRED DE FRAINE, OF WEMBLEY, AND ROBERT HENRY BICKNELL, DECEASED, LATE OF WESTMINSTER, ENGLAND, BY ROBERT ALAN WIMBERLEY BICKNELL, OF LONDON, AND ARTHUR BICKNELL, OF BIRMINGHAM, ENGLAND, LEGAL REPRESENTATIVES OF ROBERT HENRY BICKNELL, DECEASED, ASSIGNEES TO THE FRANCOIS CEMENTATION COMPANY LIMITED, OF DONCASTER, ENGLAND, A BRITISH COMPANY.

PERCUSSION TOOL FOR WAVE TRANSMISSION APPARATUS

Application filed February 28, 1928, Serial No. 257,768, and in Great Britain March 25, 1927.

This invention relates to percussion tools for operation by compressional liquid wave transmission mechanism and more particularly to the spring suspension of the tool by the aid of a body of liquid, the compressibility of which under the rapid wave transmission gives the necessary resiliency for the suspension.

In the suspension of tools of this kind it is necessary to obtain resonance between the reciprocating mass and the resilient element. As is well-known, in any spring suspension of a mass, if any predetermined natural period of oscillation is to be obtained, the resiliency or capacity of the spring suspension must bear a definite relation to the reciprocating mass which is supported and the greater the mass the more rigid must be the resilient support. For substantial masses and high periodicity of oscillation the yield of the spring suspension for a given force must be small and the compressibility of a volume of liquid is sufficient, in the case of a considerable reciprocating mass, to bring the natural period of the suspension sufficiently low to correspond to the periodicity of the wave transmission, so that resonance is established for this periodicity.

The use of liquid as a resilient body in a percussion tool has already been proposed, the liquid being divided into two volumes on opposite sides of a dividing wall belonging to the body of the tool, but according to the present invention the resilient element on which resonance depends is composed of a single body or column of liquid. Through this body or column of liquid extends the percussion or striking device or rod and according to a further feature of the invention this rod is not directly acted upon by the wave transmission, but an intermediate striking member is provided on which the wave transmission liquid operates. This intermediate member, which is preferably in the form of a sleeve mounted on the percussion rod, meets towards the end of its stroke a collar or projection on the rod and delivers the blow to the rod and thence to any percussion device which it is designed to operate. A portion of the said sleeve is disposed within a chamber con-

taining the aforesaid single body or column of liquid and is so formed that after a forward stroke has been given, the sleeve is forced back on the return wave against the operating wave-transmission liquid by the pressure in the said chamber, ready for the next forward stroke.

In order that the said invention may be clearly understood and readily carried into effect, the same will now be more fully described with reference to the accompanying drawings in which:—

Figure 1 is an axial section of one form of percussion tool constructed according to this invention, and

Figure 2 is an axial section of another form of percussion tool constructed according to this invention.

In both of the constructions shown A is the body or casing of the tool, B is the percussion rod which is arranged centrally within the body A and passes through glands A¹, A² at the rear and forward ends of the tool body, C is the working chamber to which the operating wave-transmission liquid is admitted by means of a pipe C¹ and D is the aforesaid chamber containing the single body of liquid (herein termed the liquid spring chamber) situated in the forward part of the tool body in front of the working chamber C.

Referring to Figure 1 E is the aforesaid intermediate striking member in the form of a sleeve surrounding the percussion rod B. This sleeve passes through a bushing E¹ of substantial length at the middle portion of the tool, in which bushing it has a close sliding fit, the sleeve also having a close sliding fit upon the percussion rod B. The forward end of the sleeve E is provided with a head E² forming at the rear a shoulder the surface of which is of smaller area than the forward end of the head, owing to the thickness of the sleeve itself, so that the head forms a differential piston and the pressure in the liquid spring chamber D in which the head is situated tends to drive back the sleeve. The rear end of the sleeve is open to the working chamber C to which the wave-transmission liquid is supplied so that the wave motion transmitted through the liquid acts

upon the rear end of the sleeve E and during the forward half of the wave this sleeve is forced forward at high velocity, increasing from the beginning of the wave and compressing the liquid in the spring chamber. At about the point of maximum velocity the head of the sleeve strikes a thick collar B¹ on the percussion rod and the blow is delivered to a percussion portion of the tool suitable for any desired type of operation such as percussion drilling. Following upon the delivery of the blow the compressed liquid in the liquid spring chamber D begins to return the sleeve E and during the succeeding half wave, when the pressure of the wave-transmission liquid falls to its minimum, the sleeve returns to its initial position ready for the next stroke, which begins when the compression half of the wave starts. The forward movements of the rod B are limited by the collar B¹ which comes against the rear end of a bushing A^x in which the front part of the said rod slides, and the rearward movements of the sleeve E are limited by its head E² which comes against the front end of the aforesaid bushing E¹.

As the sleeve E must be free to slide readily over the contacting surfaces and there are during each oscillation considerable differences of pressure between the liquid spring chamber D and the working chamber C receiving the operating wave-transmission liquid, leakage is liable to occur from the working chamber into the liquid spring chamber and to prevent an undesirable accumulation of pressure in the latter chamber we may provide as shown a relief valve F which opens at a predetermined pressure. The said relief valve F would be set to open at about the mean pressure in the working chamber C. This relief valve forms the subject of our United States Patent No. 1,771,672, British Patent application No. 8,281 of 1927, now Patent No. 293,088, and may be replaced by any of the equivalent devices mentioned in the specification of that application. The pipe C¹ may be provided, as shown, with a spring controlled relief valve C² similar to the relief valve F. A screw-down valve G may also be provided for controlling the flow of liquid from the working chamber C to the liquid spring chamber D through a passage A³ in the tool body. This valve is opened when the tool is to be started working so as to enable the chamber D to be filled with liquid and is closed during normal working; it can, however, be partly opened to any desired extent during working so as to vary the force of the blow of the sleeve E upon the collar B¹ of the percussion rod B.

With a single resilient body of liquid in the chamber D and an intermediate striker or sleeve E as above described, there is relatively small wear upon the packings of the percussion rod B as its movement is confined

to the small movement of the blow, while the relatively large reciprocating movement given by the wave-transmission is taken up by the said sleeve which has a long bearing surface and does not require packing as both ends of the sleeve are in liquid. 70

The construction shown by Figure 2 is similar to that shown by Figure 1 except for the omission of the sleeve E and the consequent alteration in the percussion rod B, similar parts being indicated by the same reference letters in the two figures. As a result of the omission of the sleeve E the middle portion B^x of the rod B that is situated in the bushing E¹ is made of larger diameter than the rear portion of the rod to provide an area for the operating liquid in the working chamber C to act upon; the required area for the liquid in the chamber D to act upon in order to move the rod rearwards is provided by making the front portion of the rod of smaller diameter than the middle portion as shown. A collar B² is provided for limiting the rearward movements of the rod B, and the forward movements are limited by the shoulder between the larger diameter portion and the smaller diameter front portion of the rod, the said collar and shoulder coming against the bushings E¹ and A^x respectively. 85 90 95

What we claim and desire to secure by Letters Patent of the United States is:—

1. In a percussion tool for operation by compressional liquid wave-transmission mechanism, the combination with a percussion rod and a working chamber, of a sleeve surrounding said rod with relative longitudinal movement between them, one end of said sleeve being in contact with the liquid in said chamber, and a chamber containing a single body of liquid in which the other end of said sleeve is disposed, said sleeve being so constructed that after a forward stroke has been performed it is moved back by the pressure of the liquid in the second-mentioned chamber ready for the next forward stroke. 105 110 115

2. In a percussion tool for operation by compressional liquid wave-transmission mechanism the combination with the elements claimed in claim 1, of a relief valve for the single body of liquid. 120 125

3. In a percussion tool for operation by compressional liquid wave-transmission mechanism, the combination with the elements claimed in claim 1, of a conduit between the working chamber and the chamber containing the single body of liquid, and an adjustable valve controlling this conduit. 130
